UNITED STATES PATENT OFFICE.

ARTHUR B. ALLWORTH, OF MERIDEN, CONNECTICUT, ASSIGNOR TO THE MILLER COMPANY, OF MERIDEN, CONNECTICUT, A CORPORATION OF CONNECTICUT.

LIGHTING FIXTURE.

Application filed March 18, 1925. Serial No. 16,308.

The present invention relates to lighting fixtures and is more particularly directed toward the provision of a lighting fixture having an extension cord, which extends outwardly from the canopy of the fixture and is suitably supported at a distance from the canopy to permit it to hang free of the parts of the lighting fixture carried below the canopy. Devices of this type are particularly useful in providing convenience outlets for fixtures such as kitchen fixtures.

The present invention contemplates an improved device of this type wherein the cord supporting means is entirely independent of the devices which are used in supporting or mounting the lighting fixture on the outlet box or other support. By making these parts independent of one another one is enabled to provide parts each of which is better adapted for its respective purpose, and also the entire fixture may be more easily assembled and installed.

It is therefore an object of the present invention to provide a lighting fixture canopy with a laterally extending member, either permanently or semi-permanently attached to the canopy, and to so place this member that it may readily support the extension cord. Where the canopy is made of sheet metal, as is common in making kitchen fixtures, the present invention contemplates utilizing a wire loop attached to the sheet metal stamping. A convenient way of doing this is to roll the edge of the stamping over the loop, leaving a portion of the loop extending outwardly to provide the cord support.

While the embodiment of the present invention to be shown and described in detail is a kitchen fixture having a sheet metal canopy it is to be understood that the invention may be applied to other styles of lighting fixtures made of other materials.

The accompanying drawings show, for purposes of illustrating the invention, one of the many forms in which it may be embodied.

In these drawings:

Figure 1 is a sectional view, with parts in elevation of a lighting fixture provided with the present cord supporting means;

Figure 2 is a top plan view of the lighting fixture; and

Figure 3 is a section taken on the line 3-3 of Figure 1.

The kitchen unit shown in the drawings includes a canopy 10, a globe supporting shell 11, a globe 12, socket 13, lamp 14, and suitable devices for supporting the unit and carrying the extension cord. One form of device for supporting the unit may be a U-shaped strap 15 whose lower ends are bent outwardly as shown at 16 and 17 and threaded to receive screws 18 and 19. These screws pass through holes 20 and 21 in the canopy and nuts 22 and 23 of any desired shape may be threaded into the screws to clamp the canopy on to the strap. The strap is provided with a central hole 24 to receive a crow foot 25, hickey or gas pipe and with slots 26 and 27 to receive screws for attaching the strap to the lugs of outlet boxes. It will thus be seen that the strap may be attached to any of these devices and the fixture connected thereon as a unit.

As here shown the extension cord supporting means is in the form of a wire loop 30. This loop is permanently attached to the canopy by rolling the upper edge 31 of the sheet metal stamping about the wire. A portion of the rolled edge is cut away as indicated at 32, and the wire loop is carried laterally out from the canopy as shown at 33 and 34, to provide a laterally extending member adapted to lie adjacent the ceiling. The outer end of the loop is bent downwardly as shown at 35 and a bushing 36 is supported in this downwardly bent portion. In order that the extension cord may be safely passed through the canopy, a bushing 36 is placed in the upper part of the canopy, preferably directly underneath the exposed part of the wire loop. An extension cord 8 is passed outwardly from the canopy and through both bushings, and is allowed to hang downwardly as indicated. The cord is thus supported to hang free of the globe 12.

In manufacturing the fixture, the wire loop is formed to shape and is permanently fastened to the canopy, and in mounting the fixture the loop, extension cord, and other parts may be handled as a unit and readily attached to the depending screws 18 and 19 carried on the ceiling support. There is no tendency for parts to pull out of place or be otherwise dislodged or lost. The canopy may be attached and brought close to the ceiling and the wire loop is sufficiently flexible so that any unevenness in the plaster

is compensated for. The mounting plate and wire may assume any desired angular position.

It is obvious that the invention may be embodied in many forms and constructions and I wish it to be understood that the particular form shown and described is but one of the many forms. Various modifications and changes being possible, I do not in any 10 way limit myself with respect thereto.

I claim:

1. A lighting fixture comprising a sheet metal canopy, a device attachable to a ceiling support and to which the canopy is 15 movably attached, a wire loop, the upper edge of the canopy being rolled about the wire loop, a portion of the loop projecting laterally from the canopy, and a cord supporting bushing carried on the outer end of 20 the loop.

2. A lighting fixture comprising, a canopy, a wire loop, the upper edge of the canopy being rolled over upon the wire loop, a portion of the loop projecting laterally 25 from the canopy, and a cord-supporting bushing carried at the outer end of the loop.

3. A lighting fixture having a canopy provided with an upper peripheral rolled edge, a length of wire carried within said 30 rolled edge, the wire projecting laterally outside said canopy and being bent downwardly, and a cord-supporting bushing carried in said downwardly bent portion.

4. In a lighting fixture, a lighting unit 35 comprising a canopy, a lamp socket and globe support attached to and supported from the canopy, a laterally extending cord supporting member carried by the canopy, an extension cord passing through the canopy 40 and supported by a cord supporting bushing carried in the free end of the member, said cord being connected to the lamp

socket and connectible to supply leads, and a supporting strap detachably carried by the canopy and independent of the cord supporting member, whereby the assembled lighting unit may be attached to the strap after it has been mounted. 45

5. In a lighting fixture, a lighting unit comprising a sheet metal canopy, a lamp 50 socket and globe support attached to and supported from the canopy, a laterally extending cord supporting member permanently carried in the canopy, the canopy and member having bushings, an extension 55 cord passing through said bushings and connected to the lamp socket and connectible to supply leads, and a supporting strap detachably carried by the canopy and independent of the cord supporting member, whereby the assembled lighting unit may be 60 attached to the strap after it has been mounted.

6. In a lighting fixture, a lighting unit comprising a sheet metal canopy having a 65 peripheral rolled edge, a lamp socket and globe support attached to and supported from the canopy, a laterally extending cord supporting member in the form of a bent wire permanently carried in said peripheral 70 rolled edge of the canopy, the canopy and member having bushings, an extension cord passing through said bushings and connected to the lamp socket and connectible to supply leads, and a supporting strap detachably carried by the canopy and independent of the cord supporting member, whereby the assembled lighting unit may be 75 attached to the strap after it has been mounted.

Signed at Meriden, in the county of New Haven and State of Connecticut, this 14th day of March 1925.

ARTHUR B. ALLWORTH.
